UNITED STATES PATENT OFFICE.

DANIEL O'HERN, OF JOLIET, ILLINOIS.

RAILWAY-TRACK CROSSING.

Application filed April 22, 1922. Serial No. 556,066.

To all whom it may concern:

Be it known that I, DANIEL O'HERN, a citizen of the United States, residing at Joliet, in the county of Will and State of Illinois, have invented certain new and useful Improvements in Railway-Track Crossings, of which the following is a specification.

My invention relates to railway track crossings and has particular reference to a crossing whereby one set of the intersecting rails are continuous and are not broken as is the usual permanent type of railway track crossing.

Another and further object of my invention is the provision of a railway track crossing having one set of rails extending continuously through the crossing and with the other set terminating at first mentioned set of rails and secured thereto so that a crossing is formed which is very durable in service and economical in operation, and which will stand up in hard usage with a minimum of repair.

Another and further object of my invention is a provision of a railway crossing, which while substantial and efficient in operation, allows trains to pass thereover with a minimum of shock and without the usual pounding and noise common to railway crossings as trains of cars pass thereover.

Another and further object of my invention is the provision of a crossing which is easily and simply installed and which can be placed in service with a minimum expense, without the engineering services usually necessary to the installation of crossing of this character. Therefore, this crossing can be installed in almost any place regardless of whether the tracks cross at right angles or otherwise and can be easily constructed on the ground with the tools and equipment carried by a section man and the like, instead of being specially constructed, and then moved into position, as is common with railway crossings.

These and further objects of my invention will be more fully and better understood by referring to the accompanying drawings in which—

Figure 1 is a plan view of my improved railway crossing;

Figure 2 is a detail view partially in sec-

tion and partially in elevation along lines 2—2 of Figure 1; and

Figure 3 is an enlarged detail plan view of the section of crossing shown in Figure 2.

Referring now specifically to the drawings, and in which is shown a track composed of a pair of parallel continuously extending rails 10 and 11, with a pair of parallel extending tracks 12 and 13 forming the intersecting track composed of a plurality of rail sections as will be more fully described hereinafter. The tracks 12 and 13 are composed of outside rails 14 and 15, extending up to and abutting against the rail 10, intermediate sections 16 and 17 being placed between the rails 10 and 11 at an angle thereto, and terminating adjacent each of said rails at each of their ends, and outside rails 18 and 19 which form a continuation of the tracks 12 and 13, one end of each of these rails terminating adjacent the rail 11.

Referring now specifically to Figures 2 and 3, wherein is shown the manner of joining the rails forming the crossing, the rail 19 has a base 19^a, a head 19^b, and a connecting web 20 for the said base and head. The rail 19 extends up to the rail 11 and is secured in position by means of a pair of curved bars 21 and 22, the said bars being curved and extended along the web of the rail 19 and also along the web 11^a of the rail 11 on the outside thereof, the bars 21 and 22 being turned in opposite directions. Bolts 25 pass through the web 11^a of the rail and through the bar 21 at one of its ends, with similar bolts 25^b passing through the rail 19 and the bars 21 and 22 so the rail 19 is held in position. Similar curved bars 23 and 24 lie against the web 11^a of the rail 11 on its opposite side from the bars 21 and 22 respectively, and are held in position by means of the bolts 25, 25, at one of its ends and by other bolts 25^c at its other end which pass through the rail 16 and through one end of the bar 23 with bolts 25^d passing through the bars 22 and 23 and the continuous rail 11 so that a structure is formed which is held tightly together with enough elasticity so that danger of breakage is avoided and crossing shocks reduced to a minimum. The crossing is secured together at each of its corners by simi-

lar bars just described. The base 19^a of the rail 19 is positioned slightly above the base of the rail 11, the bars 21 and 22 being curved slightly downward so that these bars 5 are properly positioned against the web of the rail 11. The head 19^b of the rail 19 is cut away at 26 so as to provide clearance for the outer portion of the car wheel 27 and the head 28 of the rail 16 is also cut 10 away at 29 so that sufficient clearance is allowed for the flange 30 of the wheel 27. The head of the rail 11 has a recess 31 there- 15 in extending transversely thereacross, which is adapted to receive the flange 32 on the wheel 33 which travels upon the rails 19, 16 and 15 respectively, and transversely across the rail 11. The wheel 33 contacts with the head 28 of the rail 16 until it reaches the point 29 and thereafter the 20 flange 32 is received into the recess 31 simultaneously as the wheel 33 leaves the rail head 28, and as the wheel 33 passes over the rail 11, the weight of the car is carried by the flange 32 in the recess 31, and as the 25 flange 32 leaves the recess 31, the tread portion of the wheel engages upon the rail head 19^b at the sloping portion 26 so that the wheel 33 passes across the rail 11 in a sub- 30 stantially even plane without shock or pounding which is common to crossings where the rails are bolted into position with 35 various forms of castings and the like. The car wheels, traveling upon the rail 11, pass over the recess 31 which is quite narrow and 40 in proper alignment with the heads 28 and 19^b without shock or jolting and thus the crossing is able to better withstand the wear to which crossings are subjected. The 45 recess 31, as will be noted, is quite shallow and is not deep enough to destroy or weaken the rail 11 so that the wheel 27, passing over the comparatively narrow recess 31 in the rail 11, does so without shock or pounding which is common to railway crossings. The 45 structure shown in detail in Figures 2 and

3, is the same at each of the opposite corners of the crossing so that the whole structure is held solidly together.

The rail heads 19 and 28 are tapered laterally at 34 and 35 so that the flange 32 of the wheel 33 will not strike against the rail heads, thus probably resulting in the wheel jumping the track, but the flange follows the crossing in the groove 31 so that the outer periphery of the wheel 33 engages 55 upon the rail head 19 as the wheel has passed over the rail 11.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In a railway crossing the combination of a pair of continuous rails extending through said crossing, a plurality of intersecting rails forming an intersecting track, the ends of said intersecting rails terminating adjacent the continuous rails and a plurality of curved bars connecting the ends of said intersecting rails to said continuous rails.

2. In a railway crossing a pair of continuous rails extending through said crossing, a plurality of intersecting rails whose ends terminate adjacent the continuous rails and a plurality of brackets for securing the ends of said intersecting rails to the continuous rails, the head of said intersecting rails being positioned slightly above the heads of the continuous rails and having sloping shoulders at the ends thereof whereby the shocks are reduced to a minimum.

Signed at Joliet, Illinois, this 11th day of April, 1922.

DANIEL O'HERN.
